(57) **CLAIM**

The ornamental design for an electric ratchet wrench, as shown and described.

DESCRIPTION

FIG. 1 is a front perspective view of an electric ratchet wrench in accordance with our new design;

FIG. 2 is a rear perspective view of the electric ratchet wrench in accordance with our new design;

FIG. 3 is a front elevational view of the electric ratchet wrench in accordance with our new design;

FIG. 4 is a rear elevational view of the electric ratchet wrench in accordance with our new design;

FIG. 5 is a top plan view of the electric ratchet wrench in accordance with our new design;

FIG. 6 is a bottom plan view of the electric ratchet wrench in accordance with our new design;

FIG. 7 is a right side elevational view of the electric ratchet wrench in accordance with our new design;

FIG. 8 is a left side elevational view of the electric ratchet wrench in accordance with our new design; and,

FIG. 9 is a front perspective view showing a state in which a battery is attached to the electric ratchet wrench in accordance with our new design.

The broken line showing of environmental structures in the drawings forms no part of the claimed design.
